STOCKING

Karl Zabel, Ephrata, Pa.

Application March 6, 1950, Serial No. 8,339

Term of patent 7 years

(Cl. D47—7)

To all whom it may concern:

Be it known that I, Karl Zabel, a citizen of the United States, residing at Ephrata, in the county of Lancaster and State of Pennsylvania, have invented a new, original, and ornamental Design for a Stocking, of which the following is a specification, reference being had to the accompanying drawing, forming a part hereof.

Figure 1 represents a perspective view of a stocking embodying my new design, as it appears when worn on the human leg;

Figure 2, a rear elevation of a portion of said stocking as it appears when worn on the human leg; and, said stocking as it appears when worn on the human leg.

I claim:

The ornamental design for a stocking, substantially as shown.

KARL ZABEL.
